(57) **CLAIM**

The ornamental design for a portable information terminal unit, as shown and described.

DESCRIPTION

FIG. 1 is a front perspective view of a portable information terminal unit, showing my new design;

FIG. 2 is a perspective view thereof showing a state in which a dial key is drawn out;

FIG. 3 is a front elevational view of the portable information terminal unit showing a closed state;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof;

FIG. 9 is a front elevational view thereof showing a state in which a dial key is drawn out; and,

FIG. 10 is a right side elevational view thereof showing a state in which a dial key is drawn out.
